CRANE BOOM POINT WHEEL CART

Alfred G. Reapsummer, 9/6 Crane Carts, 1020 NE.
44th St., Fort Lauderdale, Fla. 33309

Filed Apr. 26, 1967, Ser. No. 6,844

Term of patent 14 years

(Cl. D14—3)

FIG.1

FIG.2

FIG.3

FIG. 4

FIG. 5

FIG. 6

FIG. 1 is a perspective view of a crane boom point wheel cart embodying the new design of the present invention;

FIG. 2 is a front elevational view of the crane boom point wheel cart of FIG. 1;

FIG. 3 is a side elevational view of the side of the crane boom point wheel cart shown in the perspective view of FIG. 1;

FIG. 4 is a side elevational view of the remaining side of the crane boom point wheel cart of FIG. 1;

FIG. 5 is a top plan view of the crane boom point wheel cart of FIG. 1, and

FIG. 6 is a perspective view of a crane boom point wheel cart of FIG. 1.

The elements of a crane boom shown in broken lines are included for illustrative purposes only.

I claim:

The ornamental design for a crane boom point wheel cart, substantially as shown and described.
